UNITED STATES PATENT OFFICE.

LINNARUS E. BAKER, OF FORT WAYNE, INDIANA, ASSIGNOR TO WAYNE COMPANY, OF FORT WAYNE, INDIANA, A CORPORATION OF INDIANA.

INTERLOCKING MECHANISM FOR VISIBLE DISPENSING APPARATUS.

Application filed June 23, 1924. Serial No. 721,825.

My invention relates to improvements in liquid dispensing apparatus, particularly so-called visible dispensers adapted for outdoor use and generally used for the sale of gasoline.

Such apparatus has a valve controlling the flow of the liquid to the service pipe and another valve controlling the flow of unused liquid through the overflow or any other pipe to the source of supply.

The principal object of the invention is to prevent both these valves being open at the same time. When the operator has the serve valve open dispensing gasoline to a customer the drain-back valve must be kept closed or part of the gasoline in the container, which the customer is entitled to receive, may be drained back to the storage tank, cheating the customer. If the serve valve could be opened when the drain-back valve is open the pump owner could be cheated.

In the particular embodiment of my invention selected for illustration,

Figure 1 is a vertical axial section on the line 1—2—1—2 of Fig. 3 through the visible container (broken through horizontally for shortening), the container support and valve nest and the top of the pedestal; both the serve valve and the drain-back valve being closed and the interlocking bolt in such position that the serve valve may be opened but the drainback valve cannot be opened.

Fig. 2 is a similar view, the upper parts of the container being broken away, the drain-back valve being open and locked, and the serve valve secured in closed position by the interlocking bolt.

Fig. 3 is a horizontal section on the line 3—3 of Fig. 2.

Fig. 4, a detail of the valve mechanism only, is an elevation from the drain back valve side, and

Fig. 5 is a cross section on the line 5—5 of Fig. 4.

Referring now to the drawings, A is the pedestal of a visible liquid dispensing apparatus, a is an annular plate with peripheral flange a¹ adapted to rest on the top of the pedestal A.

The visible container B rests on a base C, which is spaced from the plate a and supported on posts a², secured in position by tie-bolts a³. A depending skirt c is secured

to the base C by bolts c⁴ and assists in housing and protecting the valves.

A preferably ornamental casing D forms the main part of the housing for the valves and is preferably made in sections held together by screw bolts d, and is readily removable without disassembling the apparatus.

The container has a top b. Within the container B, fill-pipe E terminates at a suitable height and through it from its connection e the liquid to be served is forced in any suitable manner, as by air, controlled by valve K. Also within the container B, terminates an overflow pipe F to carry back to the source of supply (not shown) excess liquid to the highest serving level.

A float meter G of any suitable form may be provided.

The liquid to be served passes through the cylindrical boss c¹, then through an L shaped fitting h on the serve valve H, then through said valve H, then through an L shaped pipe h¹ to which the serve hose (not shown) is threaded.

The unused liquid in the container B is drained back to the source of supply (not shown), flowing through the passage c² in the base C, then through an L shaped fitting i on the drain back valve I, then through said valve I, then through the post portion 85 of a T whose cross bar forms the part F¹ of the pipe F.

The serve valve H is provided with a lever h² with a flattened arm h³ integral therewith, with a hole h⁴ therethrough. Contiguous to said arm h³ is a bracket h⁵ integral with the L shaped fitting h and has a hole h⁶ adapted to register with the hole h⁴ when the valve H is closed.

The drain back valve I is provided with a lever i², with an arm i³ integral therewith, with a hole i⁴ therethrough, and a push-bolt lock i⁵ mounted in a cylindrical boss i⁷ also on said arm i³. Said push-bolt lock i⁵ has its bolt adapted to enter a hole i⁸ in a bracket i⁹ integral with the L shaped fitting i when valve I is open. Said bracket i⁹ also has a hole i¹⁰ adapted to register with a hole i¹¹ through the arm i³ when said valve I is closed.

An interlocking bar J passes through the holes h⁴, h⁶, i⁴ and i⁸ and is of such length as to enter the hole h⁴ and secure the valve H.

in closed position when in the position shown in Figs. 2 and 5; or to enter the hole i^4 and secure the valve I in closed position when in the position shown in Fig. 1.

5 With the position of the bar J shown in Figs. 2 and 5, the valve I may be opened and locked in open position by means of the push-bolt lock i^8 as shown; and when the bar J is in the drain-back position the valve

10 H cannot be opened.

In the position of the bar J shown in Fig. 1, the valve H may be opened to serve liquid to a customer, while drain-back valve I cannot be opened. Said bar J may be 15 shifted axially by pressing on the end that protrudes through a lever arm. Its movement may be limited by collars j .

I claim as my invention and desire to secure by Letters Patent of the United 20 States:—

1. In a liquid dispensing apparatus having an elevated liquid container, a service outlet, a conduit to convey liquid from said container to said service outlet, a valve in 25 said conduit, a drain conduit, a conduit to convey unused liquid from said container to said drain conduit, a valve for said last named connecting conduit, a valve lever for each of said valves, an arm on each of said

valve levers, a fixed bracket contiguous to 30 and on the inside of each of said arms, holes through said brackets and arms adapted to align with each other, and an interlocking bar adapted to pass through all of said holes when in alignment but of such length 35 as to pass through one only of said arms at a time.

2. In a liquid dispensing apparatus having an elevated liquid container, a service 40 outlet, a conduit to convey liquid from said container to said service outlet, a valve in said conduit, a drain conduit, a conduit to convey unused liquid from said container to said drain conduit, a valve for said last named connecting conduit, a valve lever for each of said valves, an arm on each of said 45 valve levers, a fixed bracket contiguous to and on the inside of each of said arms, holes through said brackets and arms adapted to align with each other, an interlocking bar adapted to pass through all of said holes when in alignment but of such length as to pass through one only of said arms at a time and means for locking said drainback valve 50 in open position.

In testimony whereof I have hereunto set my hand.

LINNAEUS E. BAKER.
